UNITED STATES PATENT OFFICE.

GARTH G. GILPIN, OF RIVERSIDE, ILLINOIS, ASSIGNOR TO UNION METAL PRODUCTS COMPANY, OF CHICAGO, ILLINOIS, A CORPORATION OF DELAWARE.

RAILWAY CAR WALL.

Application filed December 7, 1925. Serial No. 73,834.

My invention relates to the construction of railway cars and more particularly to metal end structures or walls for railway cars made of one or more metallic plates or 5 panels formed with integral reinforcing, stiffening and bracing embossments or corrugations. However, this device may be incorporated in the construction of car side walls, floors, roofs or doors used in connection with railway cars of various types.

It is well known that the end walls of railway box cars are more likely to be broken or otherwise injured than the side walls. This is due to the inertia thrusts and pressures caused by the shifting of the cargoes when the train starts or stops. These thrusts may be local, tending to distort the end in some particular spot, as, for example, when a piece of piping or lumber shifts lengthwise 15 imparting a blow against the end wall of the car; or there may be a general tendency to break out the end wall as a whole or tear it away from the framing. For the purpose, therefore, of greater strength and durability, car ends have been constructed of metal plates corrugated or formed with ribs to impart the desired strength, rigidity and resiliency.

One of the principal objects of my invention is to provide a corrugated metallic end structure for railway cars in which the corrugations have a configuration and arrangement that impart to the structure a maximum capacity for resisting cargo 30 thrusts, both local and general, static or quiescent, and with sufficient resiliency to prevent permanent distortion due to the thrusts of the loads, with a minimum weight of metal. It is important that structures 35 of this sort should be as light as is possible, consistent with strength and durability, both for reasons of economy in manufacturing cost and also to keep the weight of the car at a minimum.

40 The retaining walls of railway cars are lined to retain the cargo within the car, because a riveted joint between two flat steel surfaces will not retain such fine lading as grain, sand, etc. Steel frame (and even 45 wooden) cars are lined with wood which absorbs moisture and retards sweating. If grain was allowed to contact with a steel wall the consequent condensation of the moisture in the atmosphere would cause 50 mildew, and in such ladings as cement and

flour (even though sacked) such moisture would cause considerable damage. A wooden lining between the steel wall and the lading practically eliminates such condensation. A wooden lining also furnishes excellent 60 means for blocking bulky and package lading in place.

Any lining necessarily increases the thickness of the wall and in an end wall this means that the inside length of the car is 65 reduced or the train length of the car is increased, either of which is objectionable. It is desirable, therefore, to provide as thin a lining as possible consistent with requirements and to support the lining by means 70 which occupy the minimum possible horizontal space.

While I have shown the corrugations positioned horizontally, this is immaterial to the essential features of the invention. In 75 the preferred form, the corrugations terminate within the opposite edges of the plate. The wall may be made of one or more plates as desired.

In the drawings:

Fig. 1 is an end elevation of a railway box car with my device applied thereon.

Fig. 2 is a section on line 2—2 of Fig. 1.

Fig. 3 shows one of the embossed plates.

Fig. 4 is a side view of Fig. 3.

Fig. 5 is a section on line 5—5 of Fig. 3.

Fig. 6 is a section on line 6—6 of Fig. 3.

Fig. 7 is a section on line 7—7 of Fig. 3.

Fig. 8 shows another form of embossment.

Fig. 9 is a side view of Fig. 8.

In the form illustrated, the metallic plates extend from side to side of the car and are attached thereto and to the end sill and end plate in any convenient manner and are secured together along horizontal lines, thus 95 forming the end wall of the car.

The metallic wall is made of one or more metallic plates secured together and is reinforced by a plurality of primary embossments or corrugations formed integrally 100 therein which span the distance between the opposite side walls of the car and which are of equal depth and spaced apart distances equal to their width adjacent the middle of the car and for a short distance on either 105 side thereof. The embossments merge into each other to form a sinuous configuration to obtain resiliency.

Some of these primary embossments (1) 110 are split to form a plurality of narrower and

shallower equal width and equal depth secondary embossments 2 which are spaced apart distances equal to their width. These primary embossments may be split so as to 5 form a plurality of secondary embossments 2 at their extremities, as shown in Fig. 3, or they may be split so that the secondary embossments 3 will be adjacent their middle portion, as shown in Fig. 8. Other primary embossments (4) are intact and are 10 preferably of constant depth and constant width for the major portion of their length so as to provide a place for an attaching piece 5 and are shown 15 provided as the top and bottom of each plate. The attaching piece 5 is fitted into and secured to this embossment 4 which is preferably made straight so that the nailing strip 5 will be simple to make and to 20 apply. The lining boards 6 are positioned perpendicularly to the attaching pieces and nailed or otherwise secured thereto.

The embossments are pressed in the metallic plate so that they all protrude from the 25 same side of the plate (as shown in Fig. 5) including the secondary embossments (as shown in Fig. 6) and the attaching pieces are the same depth as the embossment into 30 which they are secured. These two features permit the lining 6 to bear against the at-

taching piece 5 and upon the plate between the primary embossments (at 7) and between the secondary embossments (at 8). A very thin lining will then meet all service requirements because it is only required to 35 support loads over very short spans.

I claim:

1. A metallic plate wall for a railway car having a plurality of equal length embossments formed therein terminating within 40 the plate adjacent its opposite edges, some of said embossments decreasing in height toward their ends and split to form shallower and narrower embossments, and other of 45 said embossments being of constant width and constant depth for the major portion of their length.

2. A metallic plate wall for a railway car having a plurality of equal length embossments formed therein terminating within 50 the plate adjacent its opposite edges, some of said embossments decreasing in height toward their ends and split to form shallower and narrower embossments, other of 55 said embossments being of constant width and constant depth for the major portion of their length, and nailing strips of constant width and constant depth secured within said other embossments.

GARTH G. GILPIN.
